Inventor:
 Thomas Peter Eusteg
 By Lawrence Haug
 Attorney.

UNITED STATES PATENT OFFICE.

THOMAS PETER EUSTEDE, OF WELLINGTON, NEW ZEALAND.

FASTENER AND RETAINER FOR CASEMENT WINDOWS, DOORS, AND THE LIKE.

1,411,482.

Specification of Letters Patent. Patented Apr. 4, 1922.

Application filed November 28, 1919. Serial No. 341,312.

To all whom it may concern:

Be it known that I, THOMAS PETER EUSTEDE, a subject of the King of Great Britain and Ireland, residing in Wellington, 5 in the Dominion of New Zealand, have invented a new and useful Improvement in Fasteners and Retainers for Casement Windows, Doors, and the like; and I do hereby declare the following to be a full, clear, and 10 exact description of the same.

The object of this invention is to provide improved means for retaining windows and doors at any desired position, and also to provide a cheaper and more compact device 15 which will at the same time be readily extensible, and therefore, form a better stay when the door or window is only slightly open, and which will, when desired, be detachable.

According hereto on the window or door post is mounted a slotted rocking shaft or the like in which one end of the stay is suitably mounted, the other end being pivoted to a rocking shaft or the like on the 25 window sash or door. The stay may be in a single part or in two or more extensible parts. A locking latch may be mounted upon the pin by which the stay is attached to the rocking shaft upon the sash. Convenient means are provided by which the stay 30 can be maintained at any desired position on the slotted rocking shaft thereby enabling the windows to be retained at any desired position. A countersunk hole is provided on 35 the slotted rocking shaft by which the stay may be made detachable and other countersunk holes may be provided at certain set positions to be an additional security against slipping.

In the drawings:—

Figure 1, is an elevation of the fastener in position.

Figure 1^a, is an elevation of the end of the stay.

Figure 2, is a side view of Figure 1.

Figure 3, is a sectional view of the slotted rocking shaft and of the hook end of the stay with the screw-pin in position.

Figure 4, is a general view of the device in 50 position on a window.

Figure 5, shows a view of the fastener with the window slightly opened.

Figure 6, shows a modified form of the device.

Figure 7, is a view of part of the under-side of Figure 6 cut off at line A—A, Figure 6.

Figure 8, is a sectional view on line B—B, Figure 6.

Figure 9, is an elevation of a modified 60 form of fastener.

Figure 10, is a side-view of Figure 9.

Figure 11 is a sectional view showing the manner in which the shoe can be clasped 65 over the rocking shaft.

In the drawings, the rocking shaft 1 is slotted at 2 and is loosely mounted on brackets 3 and 4 attached to the frame 5 of the window. The stay 6 is provided at one end with a hook 7 (see Figures 1 and 1^a) by 70 which it may be hooked upon a screw-pin 8 passing through the said rocking shaft and provided with a head 9 adapted to be fastened by the screw-pin 8 into a countersunk hole 10 in the stay 6 (see particularly Figures 2 and 3). A knurled or milled nut 11 is threaded upon the screw-pin 8 to control the head 9 in the countersunk hole 10 and to enable the stay to be retained at any desired position with regard to the slot 2 upon 75 which the stay slides. The object of the said countersunk hole 10 (see Figures 1^a, 2 and 3) is to retain the stay securely when the milled nut 11 is but slightly unscrewed. By unscrewing the milled nut 11 the head 9 80 can be pushed out of the countersunk hole 10 and the stay hook may be lifted off the screw-pin 8 and the window may thus be opened to the full extent independently of 85 the stay.

Another rocking shaft is mounted in brackets 13 and 14 on the window 15, and in such rocking shaft is pivoted at 16 one end of the extension 17 of the stay 6. A locking latch 18 is also mounted on the pivot 16 and 90 provided with a lifting knob or handle 19 for operating the latch, the hooked portion 20 of which locks over the bracket 3.

In Figure 3 is shown a sectional view of the milled nut 11 which is mounted upon the 100 screw-pin 8 of which the portion 21 passing through the outer shoe 22 and the inner shoe 23 is squared. The outer shoe 22 provides a suitable bearing surface for the end of the stay 6, while the inner shoe 23 acts as a 105 steady device for the screw-pin 8, and thereby presents a larger braking surface when the milled nut 11 is tightened. The

stay 6 being provided with an extension 17 enables the said stay to be shorter and more compact and when set at the shorter length affords a better stay when the window is 5 opened a slight distance only. The extension 17 may be dovetailed in the stay 6. The extension 17 is controlled by the milled nut 24 upon a screw-pin 25 which is preferably squared when it passes through the slot 26 10 in the extension 17 (see Figures 1 and 2). The said pin may be provided with a head 27 and may be fitted in a countersunk hole in the back of the stay 6. The milled nut 24 when tightly screwed will, at the end of 15 its extension 28, bear against the extension 17 of the stay 6.

The body of the rocking shaft 1 may be made U shaped in section as indicated in Figure 3, in which case it may be readily 20 stamped out of sheet-metal, the end of course being rounded to fit in the brackets 3 and 4. The rocking shaft 12 may be similarly constructed and, if desired, the other parts may 25 also be made of sheet-metal. The end of the bracket 3 at 29 is rounded or bevelled to enable the hook 20 of the latch 18 to trip over it readily when the window is being closed. It will be noticed on referring to Figure 1 30 that the pivoted end of the latch is partially rounded, the square portion 30 being left in order to prevent the latch from falling below the position indicated in the drawings. The rocking shaft 12 together with the 35 brackets 13 and 14 may be encased in a sheet-metal tray 31 if desired, to enable it to be readily fitted in position.

The operation of the device is as follows:—

Referring to Figures 1 and 2, in which the 40 window is shown closed, the latch 18 is lifted from the bracket 3 and the milled nut 11 being loosened the end of the stay 6, together with the shoes 22 and 23, and screw-pin 8 and the milled nut 11 will slide along the 45 slot 2 by means of the pin 8 in the rocking shaft 1 when the window is pressed outwards, as indicated more particularly in Figure 5. When the window is thus opened it may be retained at any desired position 50 by securing the milled nut 11 against the outer face of the rocking shaft 1. When the pin 8 reaches the opposite end of the slot 2 if it is desired to open the window further, the extensible sliding portion 49 of the stay 55 6 is brought into use by releasing the milled nut 24 until the extension 17 is brought to its maximum, when the milled nut is tightened (see Figure 4), and the window is thereby locked.

60 A modified form of the invention is illustrated in Figures 6, 7 and 8, in which the stay may be retained at a horizontal or approximately horizontal position when the window is but slightly opened, thereby affording a better stay. In this form of the

invention the slot 26 of the extensible portion 17 of the stay 6 is made open at the end 32 that projects into the room and another slot 33 is provided in the channelled portion of the stay 6. Consequently when the milled 70 nut 11 is partially unscrewed and the head 9 released from the countersunk hole 10, the stay 6 may be slid into the position shown in Figure 6 and may be held in position by the milled nut 11, as before. In this case it 75 may be desirable to provide means whereby the mere lifting of the head 9 out of the countersunk hole 10 will not entirely unfasten the stay 6 from the rocking shaft 1, and with this object feet or projections 80 34 are provided which project from the end of the stay 6. By further unscrewing the milled nut 11, so as to enable the head 9 to clear the feet 34, the stay may be detached and the window opened to its maximum distance, independently of the stay.

If desired, the fastener may be constructed in the form shown in Figures 9 and 10 which case both the stay and the fastener may be made straight. In this case the rocking shaft 35 is located underneath the stay 36 which is provided with an extension 37 as indicated in Figure 10. The end of the stay 6 or of the extension 37 is pivoted at 38 to a hinged piece 39 which takes the place 95 of the similar rocking shaft 12 shown in Figures 1, 2 and 5. On the other side of the hinged piece the latch 40 is pivoted on the pin 38 also and falls over a bracket 41 as before. The knob 42 controls the extension 37 in the same manner as previously, and the latch 40 is also provided with a stop 100 to prevent it from falling below the position shown in Figure 9. The shoe 43 is placed over the rocking shaft 45 and the rocking 105 shaft may be provided with a flange 44 upon which the shoe is turned over at 45 indicated in Figures 9 to 11.

As shown in Figures 9 and 10 the nut 46 threaded upon the pin 47 controls the movement of the stay 37 in a similar manner to the nut 11 shown in Figures 1 to 6, the pin 47 being squared at the portion 48 shown by crossed lines in order to prevent the pin from turning.

What I claim is:—

1. In a retainer and fastener of the kind described, a vertically disposed slotted rocking shaft secured to the window frame, a pin slidable in said slotted rocking shaft, a stay having one end thereof pivotally and slidably connected to said pin whereby the said stay may be locked to said rocking shaft, a universal coupling on the window sash at the side farthest removed from the 110 hinges, the other end of said stay connected to said universal coupling, said stay slotted for a portion of its length where it slides upon said pin whereby in all open positions of the window said stay will be sub- 120 125 130

stantially horizontal, substantially as described.

2. In a retainer and fastener of the kind described a vertically disposed slotted rocking shaft secured to the window frame, a pin slidable in said slotted rocking shaft, a stay having one end thereof pivotally and slidably connected to said pin whereby the said stay may be locked to said rocking shaft, a universal coupling on the window sash at the side farthest removed from the hinges, the other end of said stay connected to said universal coupling, said stay slotted for a portion of its length where it slides upon said pin whereby in all open positions of the window said stay will be substantially horizontal, and said stay provided with a countersunk hole near one end to receive the head of said pin to prevent said stay becoming detached when slightly unscrewing the said pin, substantially as described.

3. In a retainer and fastener of the kind described, a vertically disposed slotted rocking shaft secured to the window frame, a pin slidable in said slotted rocking shaft, a stay having one end thereof pivotally and slidably connected to said pin whereby said stay may be locked to said rocking shaft, a universal coupling on the window sash at the side farthest removed from the hinges, said stay slotted for a portion of its length where it slides upon said pin, an extensible portion guided upon said stay, said extensible portion connected to said universal coupling, and means to lock said extension portion to said stay, substantially as described.

35 4. In a retainer and fastener of the kind described, a vertically disposed slotted rocking shaft secured to the window frame, a pin slidable in said slotted rocking shaft, a stay

having one end thereof pivotally and slidably connected to said pin whereby the said stay may be locked to said rocking shaft, a universal coupling on the window sash 45 at the side farthest removed from the hinges, the other end of said stay connected to said universal coupling, said stay slotted for a portion of its length where it slides upon said pin whereby in all open positions 50 of the window said stay will be substantially horizontal, and said stay provided with a countersunk hole near one end to receive the head of said pin to prevent said stay becoming detached when slightly unscrewing the said pin, substantially as described.

5. In a retainer and fastener of the kind described, a vertically disposed slotted rocking shaft secured to the window frame, a pin slidable in said slotted rocking shaft, a stay having one end thereof pivotally and slidably connected to said pin whereby the said stay may be locked to said rocking shaft, a universal coupling on the window 60 sash at the side farthest removed from the hinges, the other end of said stay connected to said universal coupling, said stay slotted for a portion of its length where it slides upon said pin whereby in all open positions 65 of the window said stay will be substantially horizontal, a latch pivoted on said universal coupling, a bracket upon said window frame which said latch engages, substantially as described.

In testimony whereof, I have signed my name to this specification in the presence of two subscribing witnesses.

THOMAS PETER EUSTEGER.
